Attorney,

UNITED STATES PATENT OFFICE.

JAMES FINNEGAN AND WILLIAM MIES, OF FERNEY, DAKOTA TERRITORY.

WHEEL-HARROW.

SPECIFICATION forming part of Letters Patent No. 398,600, dated February 26, 1889.

Application filed September 19, 1888. Serial No. 285,806. (No model.)

To all whom it may concern:

Be it known that we, JAMES FINNEGAN and WILLIAM MIES, citizens of the United States, residing at Ferney, in the county of Brown

5 and Territory of Dakota, have invented certain new and useful Improvements in Wheel-Harrows; and we do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to certain new and useful improvements in harrows, and it has more particular reference to that class of harrows which are commonly denominated "wheel-harrows;" and it has for its object to 20 simplify the construction and to render more efficient in operation this class of harrows.

25 A further object of the present invention is to provide a wheel-harrow in which any section of the harrow may be either raised or lowered by the simple manipulation of a foot-lever without the necessity of stopping the machine, and in which the several sections may be raised from the ground when it is desired to move the machine from one point to 30 another when not in use.

35 To these ends, and to such others as the invention may pertain, the same consists in the peculiar combinations, and in the novel construction, arrangement, and adaptation of parts, all as more fully hereinafter described, 40 shown in the drawings, and then specifically defined in the appended claims.

The invention is clearly illustrated in the accompanying drawings, which, with the letters of reference marked thereon, form a part of this specification, and in which—

45 Figure 1 is a perspective view of a wheel-harrow constructed in accordance with my invention. Fig. 2 is a side view of the same with the runners in place. Fig. 3 is a top plan of the machine. Fig. 4 is a bottom plan view of the seat. Figs. 5 and 6 are details, more particularly hereinafter referred to.

50 Reference now being had to the details of the drawings by letter, A designates the axle,

and A² the wheels, of the machine. The axle A is suitably journaled to the main frame B.

B² is a platform built over the rear portion of the frame.

C is the seat resting upon suitable supports, consisting of the spring-arms C² and vertical rod C³, the upper end of said rod C³ being secured to the bottom of the seat, and its lower end passed through a hole, a, in the platform B².

55 C⁴ is a spiral spring surrounding the rod C³, the lower end of said spring having a bearing against the platform, while its upper end is in contact with the under side of the seat, as shown. It will be observed that the spring-arms C², above referred to, are the opposite ends of a single piece of spring metal, the central portion of which is coiled about a lug or extension, a², beneath the bottom of the seat, 60 as shown in Figs. 4 and 5.

65 D is an arched bifurcated rod, the downwardly-extended front end of which is provided with an eye, a³, through which is passed the bolt or pivot a⁴, by which the same is attached to the center of the draft-bar D². The 70 rear or bifurcated portion of this rod forms the main frame of the machine, as shown.

E, E², and E³ are the harrows, which may be of any approved number, form, or construction. In the present instance I have shown 80 in the drawings a series of three harrows, the outer harrows, E E³, being each rectangular in form, while the intermediate harrow, E², is substantially triangular. Each of the harrows is pivotally attached at its front end to 85 the draft-bar D², as shown.

90 F, F², and F³ are levers pivoted at their centers within suitable ears or lugs, b, upon the upper face of the transverse timber G, secured to the upper face of the frame B at a 95 point near its front end, the ends of said timber being extended a short distance beyond the sides of the frame. It will be observed that the lever F² is pivoted at substantially the longitudinal center of the timber G, and that the lever is arranged at right angles to said timber, while the levers F and F³ are pivoted at points near the opposite outer ends of the timber, and the rear ends of the levers are 100 extended inwardly toward the center of the

frame of the machine. The front end of each of the pivoted arms F, F², and F³ is connected with the rear end of the harrow beneath it by means of a suitable chain, c.

5 H, H², and H³ are foot-levers, each pivoted at one of its ends within suitable ears or lugs secured to the lower face of the timber G. The rear ends of the levers F, F², and F³ are attached to the foot-levers by means of suitable links, d, as shown.

J is a transverse timber placed at a short distance to the rear of the timber G, where it serves to strengthen the frame, and also serves to limit the upward movement of the foot-levers. K is a standard secured to the timber J, and carrying at its upper end a suitable rest or guide for the reins.

L are runners, which are placed beneath the ends of the draft-bar D², in order to rise 20 the same from the ground when it is desired to move the harrow from one lot to another. These runners may either be made detachable as I have shown them, or they may, if desired, be hinged to the draft-bar in any approved manner, so as to be in readiness at all 25 times for immediate use.

The operation of the machine is simple and will be readily understood. It will be seen that the connections described between the 30 foot-levers and the harrows render it possible for the driver to quickly and easily raise any one or more of the harrows from the ground by simply depressing the foot-lever to which the particular harrow is attached, and thus 35 obstructions may be avoided and weeds or other substances which may become clogged in the harrow-teeth may be removed.

We do not seek to claim, broadly, a harrow 40 provided with foot-levers and connections for raising and lowering the harrows, but restrict

ourselves in a measure to our particular construction and arrangement of parts.

What is claimed to be new, and desired to be secured by Letters Patent, is—

1. The wheel-harrow described, comprising 45 in combination the wheels, the frame composed of a bifurcated rod, as described, the seat supported upon the spring-arms C², and vertical rod C³, surrounded by spiral spring C⁴, the draft-bar pivoted at its center to the 50 downwardly-extended front end of the bifurcated rod, forming the frame, the foot-levers pivotally attached at their front ends to the under face of the timber G, the pivoted arms F, F², F³, pivoted to the upper face of said timber G, and the connecting-links between said 55 foot-levers, pivoted arms and harrows, all arranged and operating substantially as described.

2. The combination, with the frame, the 60 arched rod D, connected thereto, the draft-bar D², pivotally connected to the forward end of said rod, and the harrows pivotally connected to said draft-bar independent of each other, of the levers F, F², and F³, pivoted near 65 their centers to the cross-bar of the frame and pivotally connected at one end to said harrows, and the foot-levers pivotally connected at their forward ends to said cross-bar and pivotally connected to the levers F, F², and F³, to the 70 rear of their fulcrums, substantially as and for the purpose described.

In testimony whereof we affix our signatures in presence of two witnesses.

JAMES FINNEGAN.
WILLIAM MIES.
